UNITED STATES PATENT OFFICE.

JOSEPH J. SMITH, OF CAMBRIDGE, MASSACHUSETTS, ASSIGNOR TO WILLIAM FIRTH, OF CHESTNUT HILL, MASSACHUSETTS.

PNEUMATIC CLEANER.

1,245,629.

Specification of Letters Patent.

Patented Nov. 6, 1917.

Application filed May 29, 1916. Serial No. 100,664.

To all whom it may concern:

Be it known that I, JOSEPH J. SMITH, a citizen of the United States, residing at Cambridge, in the county of Middlesex and

5 State of Massachusetts, have invented new and useful Improvements in Pneumatic Cleaners, of which the following is a specification, reference being had to the accompanying drawings, forming part thereof.

10 This invention has reference to improvements in pneumatic cleaners, so called.

One object of the invention is to so construct a pneumatic cleaning machine that by a slight adjustment of the mechanism it 15 may be changed from a suction cleaning machine to a blowing machine.

Another object of the invention is to improve the machine with reference to controlling the direction in which air blasts can be 20 delivered.

Another object of the invention is to improve the construction of the machine with reference to the mounting of the fan motor and its battery.

25 Other objects of the invention will appear from the following description.

The invention consists in the novel pneumatic cleaning machine as shall hereinafter be more fully described and pointed out in 30 the claims.

Figure 1, represents the improved machine in perspective.

Fig. 2, represents a plan view of parts of the same enlarged.

35 Fig. 3, represents a side elevation of the improved machine.

Similar characters of reference designate corresponding parts throughout.

As shown in the drawings 5, 5 indicate 40 side frames having at their rear portions the vertical tubular columns 6, 6 each having the laterally extending air outlets 7 and 8 positioned as to height with relation to the machines or the points at which air cur-

45 rents are intended to be directed from said outlets. These frames 5, 5 are spaced apart by platform 9 to which said frames are attached and by the front member 10 having the passage 11 to which member 10 is se-

50 cured the neck 12 of the transversely extending inlet mouth-piece 13 which may be of suitable construction. These side frames

55 5, 5, about midway of their length have the stud shafts 14, 14 on which are journaled the wheels 15, 15 which wheels are of a di-

ameter to so sustain the machine that the outlets 8, 8 and the inlet mouth piece 13 are close to but clear of the roadway or floor on which the machine is operated.

Mounted on the upper portions of the 60 side frames 5, 5 is the fan chamber 16 which is provided with the suction fan 17 on the shaft 18 of the electric motor 19. This motor is also mounted on said frames 5, 5 and is adapted to be operated by or from a secondary electric battery B which is slidably received by the platform 9, the spacing apart of the tubular columns 6, 6 being such as to readily permit the passage of said battery therebetween.

70 Passage 11 is connected with fan chamber 16 by means of the pipe 20 having in its wall the opening 21 furnished with the hinged door or closure 22 adapted, under certain conditions, to be sustained in the 75 closed position by the spring latch 23. This door 22 is hinged to swing into the pipe 20 to the position indicated in dotted lines in Fig. 3 and, when in such position, acts as a damper to close the passage 11 so that the 80 action of fan 16 is to draw air inward through the opening 21 of said pipe 20.

At the upper ends of the columns 6, 6 is mounted the plate 24 having the openings 25 and 26, 26 the latter of which are in registry with said columns 6, 6 and are furnished with the slideable slotted damper plates 27, 27 adapted to be adjusted to control the size of said openings 26, 26. At the upper end of fan chamber 16 is the swivel 90 joint 28 in which is mounted one end of the elbow 29 the other end 30 of which is adapted to be swung into registry with either of the openings 26, 26 of plate 24 to deliver to either of the columns 6, 6. This 95 end 30 of elbow 29 has the latch 31 which is engaged beneath the curved lip 32 mounted on plate 24.

The dust or refuse receptacle 33 is adapted to slide into position on the platform 9 100 partially between the columns 6, 6 and has at its upper end an opening adapted to register with the opening 25 of plate 24.

Provision is made to move the machine 105 from place to place by means of the handle 34 having the rigid arms 35, 35 attached to the machine.

In the operation of the machine as a suction cleaner the door 22 is swung to the closed position as shown in full lines in 110

Fig. 3. Fan 17 is operated by its motor to draw air inward through the mouthpiece 13 and such air, with dust, waste or refuse carried by the air will pass through the fan chamber 16 into the elbow pipe 29 and thence through the opening 25 of plate 24 to the receptacle 33. During such operation the machine may be moved about the floor which is under process of cleaning and, particularly, the machine may be moved along an aisle between two lines of looms, spinning frames or other machines.

The machine is prepared for use as a blowing machine by releasing the door 22 from the latch 23 and swinging said door inward to the position indicated in dotted lines in Fig. 3, the weight of this door 22 being sufficient to retain it in this position. The free end of elbow pipe 29 is swung into registry with one of the openings 26, 26 of plate 24 depending upon the direction in which it is desired to deliver air. Motor 19 is now started and fan 17 is operated with the result that air is drawn inward through the opening 21 and after passing through fan chamber 16 and elbow 29 is delivered to one of the columns 6, 6 in suitable pressure and volume, controlled somewhat by the damper 27, and issues from the outlets 7 and 8. The air issuing from the outlet 8 acts or tends to blow dust and light material along the floor laterally of the path of the machine while the air issuing from the outlet 7 has a tendency to blow the dust, rising from said lower air currents, also laterally and tends to prevent undue rising of said dust.

The outlets 7 are preferably located, as to height above the floor on which the machine is to operate, with relation to the height of some part of a machine on which dust

usually accumulates, as one of the rails of a spinning frame, with the view that as this improved cleaner is moved along past a machine to be cleaned, dust and lint will be blown through said machine to be cleaned as well as along the floor under said machine so that said dust and lint will accumulate in the next aisle, to be taken up by this improved cleaner when operated through said next aisle as a suction cleaner.

Having thus described my invention I claim as new and desire to secure by Letters Patent.

1. A pneumatic cleaning machine of the nature described comprising a frame having a pair of wheels on which said frame is balanced, an air inlet located transversely in front of said wheels, a pair of air outlets located back of said wheels, an air chamber connected with said inlet, means to create a current of air in said chamber, and mechanism for connecting said chamber with either of said outlets.

2. A pneumatic cleaner of the nature described comprising a frame having side members, an air inlet mouthpiece at the forward end of said frame, a fan chamber, a pipe communicating with said mouthpiece and with said fan chamber and having an opening, a closure for said opening adapted to swing into said pipe to interrupt passage from said mouthpiece, a pair of tubular columns mounted on said frame and having air outlets and inlets, a dust receptacle carried by said frame and having an inlet, and a pipe pivotally mounted in communication with said fan chamber and adjustable to connect its free end with the inlet of said receptacle or with either of said inlets of the respective columns.

JOSEPH J. SMITH.
